FIG 20.3
by *Geo. P. Kimmel*

Attorney

UNITED STATES PATENT OFFICE.

WEBB W. MARKWOOD, OF CAMBRIDGE, MINNESOTA.

BRACKET BED-TABLE.

1,295,182.

Specification of Letters Patent. Patented Feb. 25, 1919.

Application filed January 18, 1918. Serial No. 212,452.

To all whom it may concern:

Be it known that I, WEBB W. MARKWOOD, a citizen of the United States, residing at Cambridge, in the county of Isanti and 5 State of Minnesota, have invented certain new and useful Improvements in Bracket Bed-Tables, of which the following is a specification.

This invention relates to new and useful 10 improvements in supports for a bed table, and the primary object of the invention is to provide an attachment which is adapted to be easily applied to a bed, whereby a small table is positioned horizontally above 15 the bed, and said table being supported in such a manner, that it is capable of being positioned at various angles, and being so constructed that the support may be folded to swing the table out of the way when desired.

Another object of the invention is to provide a bed table attachment of this character 20 provided with a support, which is especially adapted to be applied to the side rail of a bed, and which may be easily connected with, or removed from the same.

A further object of the invention is to provide a bed table attachment of this character which includes a pair of horizontal 25 and vertically disposed telescopic standards, which are hingedly connected, said standards having one of their free ends connected with the bed rail, while the other supports a table thereon, whereby the table may be 30 easily removed from or placed in position over a bed.

A still further object of the invention is to provide a support of this character, that is detachably connected with a small table 35 at its outer end, said connection including a spring catch, that automatically secures the table to the end of the support, when the same is positioned thereon.

Still a further object of the invention is 40 to provide a device of this character which is easily and simply constructed, inexpensive to manufacture, and one which will be very efficient in operation.

With these and numerous other objects in 45 view, my invention consists in the novel features of construction, combination and arrangement of parts, which will be herein referred to and more particularly pointed out in the specification and claim.

50 In the accompanying drawings,

Figure 1 is a side elevation of the table attached to a section of a bed,

Fig. 2 is a fragmental vertical section through the table and bracket,

Fig. 3 is a fragmentary bottom plan of 60 the same, and,

Fig. 4 is a detail in perspective of the bracket receiving element.

In describing my invention, I shall refer to the drawings in which similar reference 65 characters designate corresponding parts throughout the several views.

The numeral 1 designates the side rail of an ordinary bed, which forms the stationary support, upon which the attachment is secured. 70 This attachment is especially adapted to be applied to the side rail of an iron bedstead, but the same is not limited to this application, as it may be secured to any stationary support, where the use of an attachment of this character is found desirable.

The attachment comprises a supporting means 2, which includes broadly a vertical standard 3, and a horizontal support 4, 80 which have their ends hingedly connected as shown at 5. The lower end of the vertical standard 3 is provided with an outwardly extending apertured foot 6, which is adapted to be positioned on a railing 85 clamp or bracket 7, which has its upper portion apertured to aline with the aperture in the foot 6 of the vertical standard 3.

The railing clamp is formed with a downwardly extending curved part at one edge 90 thereof, which is adapted to hook under the vertical portion of the bed rail 1, and disposed adjacent the extremity of the bent portion, is a clamping screw 8, which is adapted to engage the bed rail. Positioned 95 through the alining apertures in the foot 6, and top 7 of the railing clamp, is a locking screw 9, which clamps these parts in position. By this construction, it will be obvious that the vertical standard 3 may be 100 securely attached to the side rail of the iron bedstead, by moving the said screws 8 and 9 to operative position. The standard 3 will be held vertically, substantially in the plane of the vertical portion of the bed rail. 105

The vertical standard 3 is formed in two telescopic sections 10 and 11, the upper section 11, having one portion of the hinge 5 detachably and rotatably connected therewith while the lower section 10 has its lower 110

end formed with the foot 6, that connects with the bracket that clamps to the bed rail. These two sections are adapted to be held in various adjusted positions with respect 5 to each other, by means of a set screw, that is positioned through the lower section 10.

The horizontally disposed or upper section 4 of the support, is formed similarly to the lower standard 3, that is it may be comprised of two slidably engaged sections 13 and 14, the section 13 having its outer end forming one portion of the hinge 5, and the section 14 is adapted to be connected with the table 15, in a manner to be herein- 15 after more fully described. These two sections are likewise held in various adjustable positions by means of a set-screw, whereby they may be adjusted to extend the desired distance across the bed when the support 20 is in position.

The other end of the section 14 of the horizontally extending standard 4, is off-set as shown at 16, and the same has extending transversely across to the bottom thereof ad- 25 jacent this extremity a slot 17 for purposes to be hereinafter more fully described. The outer end of the section 14 is inclined as shown at 18. A casing 19 has projecting securing ears 20 formed on its outer edge at 30 the top thereof, said ears being adapted to be flush against the bottom of the table and to receive fastening members therethrough, to secure the casing in position. The outer edge of the casing is provided with an up- 35 turned lip 21, that extends over one edge of the table, intermediate the ends thereof, and which receives the off-set portion of the section 14, as will be hereinafter described. The casing 19 is provided with a transversely 40 extending slot 22 therein, which receives the base portion of a bent spring clamp 23, which is substantially U-shaped having the extremities of its arms secured to the opposite sides of the casing as shown at 24, and said arms 45 normally extending parallel with the casing, then projecting outwardly at right angles, to the base portion, which is normally positioned within the slot. When the end of the section 14 is forced within the casing 19, the inclined extremity 18 thereof will lift the spring 23, and when the slot 17 in the extremity of the section is positioned beneath the spring, the base of said spring will drop therein, thus securely locking the end of the 50 section against withdrawal. This will securely support the table 15 on the end of the standards 4.

In operation the device is positioned, as clearly shown in Fig. 1 of the drawings, the 55 rail engaging clamp that is connected with the lower end of the standard 3, will be se-

curely engaged about the side rail 1 of a bed. The standards 3 and 4 being normally positioned at right angles, will cause the table 15 to be arranged in a substantially horizontal plane over the bed. As the standards 3 and 4 are longitudinally adjustable, owing to their telescopic construction, it is obvious that the device may be adjusted vertically or horizontally to the desired degree. When not in use, the horizontally disposed standards may be swung upwardly and outwardly, and then down parallel with the standards 3, whereby the table will be out of position. If desired the table may be removed from the end of the standard 4, by releasing the spring 23, and withdrawing the table from the off-set portion of the standard.

This attachment will be found especially useful for sick beds, as the support is capable of various adjustments to hold the table or platform at any desired angle. It may be used for supporting a book, a light, meals, etc., in the easiest and most accessible position desired. The attachment owing to its extremely simple construction, may be easily removed, and folded, so that it will occupy a very small space.

From the above description taken in connection with the accompanying drawings, it is thought that a clear and comprehensive understanding of the construction, operation, and advantages of my invention may be had, and while I have shown and described the device as embodying a specific structure, I desire that it be understood that such changes may be made in said structure as do not depart from the spirit and scope of the invention.

Having fully described my invention, what I claim as new, and desire to secure by Letters Patent, is:

A device of the character described including supporting arms, the free extremity of one of said arms being offset and recessed, attaching means engaged with the free extremity of the remaining arm, a table, a casing having an abutment formed on one end thereof secured to the under side of said table adjacent one marginal portion thereof and having slots formed in the side and top walls thereof, and a substantially U-shaped spring catch secured at its opposite ends to the sides of the casing and adapted to be received in the slots formed in the side and top walls thereof and in the recessed offset extremity of said arm, the intermediate portions of the sides of the spring being looped.

In testimony whereof, I affix my signature hereto.

WEBB W. MARKWOOD.
